UNITED STATES PATENT OFFICE.

HENRY L. ZABRISKIE, OF WESTFIELD, NEW JERSEY, ASSIGNOR TO DIEHL MANUFACTURING COMPANY, OF ELIZABETH, NEW JERSEY, A CORPORATION OF NEW JERSEY.

CENTRIFUGAL SWITCH.

1,155,985.

Specification of Letters Patent.

Patented Oct. 5, 1915.

Application filed July 10, 1913. Serial No. 778,343.

To all whom it may concern:

Be it known that I, HENRY L. ZABRISKIE, a citizen of the United States, residing at Westfield, in the county of Union and State 5 of New Jersey, have invented a certain new and useful Improvement in Centrifugal Switches, of which the following is a full, clear, and exact description.

This invention relates to centrifugal switches for electrical apparatus, and more particularly to such switches as applied to single phase alternating current or induction 10 motors.

In such motors an auxiliary starting winding 15 is used and it is desirable to cut out this winding when the rotor of the motor approaches synchronous speed, and it is the object of this invention to provide a switch automatically operated by the centrifugal 20 action of the rotor for cutting out this winding.

The invention consists of a number of contact fingers pivotally mounted with relation to the complementary contact surfaces and 25 normally held in circuit making contact with said complementary members by means of pairs of springs so disposed with relation to the fingers as to be sensitively responsive to centrifugal action to break the circuit 30 automatically, as desired, upon the occurrence of conditions requiring such breaking of the circuit, and equally sensitive to respond to conditions requiring the making of the circuit again, as I will proceed now to 35 explain and finally claim.

In the accompanying drawings illustrating the invention, in the several figures of which like parts are similarly designated, Figure 1 is a front elevation of the switch 40 with the contact fingers in flexed position. Fig. 2 is an elevation looking in the direction of arrow α , Fig. 1. Fig. 3 is a section taken on line A B of Fig. 1. Fig. 4 is a view similar to Fig. 1, but showing the contact fingers in their extreme depressed position. Fig. 5 is a front view of a suitable contact piece for use with the contact fingers of the switch.

1 is a plate of sheet metal stamped and 50 shaped in such a way as to form upstanding ears 2 and arms 3. The arms 3 are arranged in pairs, preferably three, and between each pair is mounted a contact finger 4, having its axis 5 of vibration arranged at the upper

portions of the arms. The contact fingers 4 55 have formed integral therewith contact tips 6 for coöperation with suitable contact plates to make and break the circuit, and stop members 7 which latter are adapted to limit the movement of the fingers 4 by striking 60 against one of the arms 3. The fingers 4 are so pivoted that the greatest weight is between the pivotal point and the plate 1. These weighted ends of the fingers are pierced at points 8 substantially farthest 65 removed from the axes, and said weighted ends are connected outside of the radius of the axial points with the ears 2 by helical springs 9. Each finger has two of these springs attached to it, one on each side and 70 extending therefrom at an angle, and the opposite ends of these springs are attached to the ears 2. The ears being stationary and the points of attachment of the springs to the fingers being movable in the arc of a 75 circle about the axial points 5, the points of attachment of the springs to the ears 2 will be centers for the oscillatory movement of the springs. These ears are of such a height that a line drawn from the spring 80 attaching point of one of them to the point 8 of one of the fingers 4 when its tip 6 is in its lowermost position, will be almost on a line with the axial point 5 of the fingers 4 at a point opposite such axial point. It will 85 thus be seen that when the fingers 4 are depressed fully the axes of the springs 9 will rise nearly as high as the axial points of the fingers 4. In this way a very quick and effective spring action is obtained and very 90 little resistance is offered to the centrifugal action of the fingers 4.

The plate 1 is mounted upon a disk 10 of suitable insulating material, which forms a base by which the switch may be mounted 95 upon the rotor of the motor.

The complementary part of the switch is formed preferably of two contact plates 11 (Fig. 5) mounted upon the casing of the motor and insulated therefrom and from 100 each other by a disk 12 of suitable insulating material. These plates 11 are connected by wires 13 with the motor windings. A raised portion 14 on the faces of the plates 11 forms a contact surface against which 105 the tips 6 of the fingers 4 are normally held by the springs 9. It will of course be understood that these contact plates are mount-

ed at right angles to the axis of the motor shaft and parallel with the plate 1.

The operation of the switch is as follows: The motor being at rest, the tips 6 of the 5 contact fingers 4 will be bearing against the raised portion of the contact plates 11 under the pressure of the springs 9, and as there are three fingers 4 and only two plates 11, it will always be possible for a circuit to be 10 made through the switch. The electric current being turned on, it will electrify the starting windings of the motor through the switch and cause the rotor to revolve. As the speed of revolution increases, the centrifugal action upon the weighted ends of the 15 fingers 4 will tend to cause them to fly out against the tension of the springs 9 so that when the rotor has attained a synchronous speed the circuit made by the switch will be 20 broken and the motor will run by the main windings.

It will be noted that as the contact fingers 4 fly out under centrifugal force the lines of action of the springs 9 tend to come 25 toward a dead center, thus giving a very quick and effective spring action.

While the invention is designed primarily for use on motors of the character first described, it is not intended to limit it or the 30 scope of the claims to any particular use. Obviously, therefore, it is within my invention to use the principle of the switch with and without structural alterations wherever it is adaptable.

35 What I claim is:—

1. A centrifugal switch, comprising a plate having fulcral arms and ears, contact fingers intermediately pivoted between said arms, springs interposed between said fingers and ears and engaging the fingers at points most remote from their contact ends, and contact plates arranged parallel with said plate and with which said springs normally hold said fingers in circuit-making 45 contact.

2. A centrifugal switch, comprising a plate having arms and ears, contact fingers pivotally mounted between said arms, and a pair of springs attached to each finger and to 50 said ears on opposite sides of each finger for

normally holding said fingers in circuit-making position.

3. A centrifugal switch, comprising a plate having fulcral arms and ears, contact fingers pivotally mounted between said arms, 55 and a pair of springs connected to each finger and to said ears on opposite sides of each finger, said ears being stationary and each finger movable in an arc of a circle about its axis, and the points of attachment of the springs to the ears affording centers for oscillatory movement of the springs, so that the tension of said springs remains substantially constant under the movement of the fingers. 60

4. A centrifugal switch, comprising a plate having fulcral arms and ears stamped up therefrom, contact fingers pivotally mounted between said arms, complementary contact plates arranged at right angles to the axis 70 of the motor shaft and adapted to be engaged by said contact fingers, and a pair of springs attached to each finger and to said ears on opposite sides of each finger for holding said fingers in engagement with said 75 contact plates.

5. A centrifugal switch, comprising a plate having fulcral arms and ears stamped up therefrom, counter-weighted contact fingers pivotally mounted between said arms, and a 80 pair of springs connected to the counter-weighted end of each finger and to said ears on opposite sides of each finger and outside of the radius of revolution of the pivotal points of said fingers. 85

6. A centrifugal switch, comprising a plate having pairs of arms, contact fingers eccentrically pivoted between said arms and provided with stops to limit their movement in one direction, ears rising from said plate, 90 and springs pivotally mounted in said ears and connected with said contact fingers and adapted to rise and fall with said fingers as they turn upon their pivots.

In testimony whereof I have hereunto set 95 my hand this 7th day of July A. D. 1913.

HENRY L. ZABRISKIE.
